UNITED STATES PATENT OFFICE.

HALBERT K. HITCHCOCK, OF PITTSBURGH, PENNSYLVANIA.

METHOD AND APPARATUS FOR GRADING FINELY-DIVIDED MATERIAL.

1,319,771.

Specification of Letters Patent.

Patented Oct. 28, 1919.

Application filed August 9, 1915. Serial No. 44,625.

To all whom it may concern:

Be it known that I, HALBERT K. HITCHCOCK, a resident of Pittsburgh, in the county of Allegheny and State of Pennsylvania, have invented a new and useful Improvement in Methods and Apparatus for Grading Finely-Divided Material, of which the following is a specification.

This invention relates to method and apparatus for grading or classifying finely divided material, such as sand, emery or other abrasive materials to be used, for example, in grinding or polishing plate glass, or as binders in ceramics, or any other finely divided material. The invention is an improvement upon that shown, described and claimed in my Patent No. 1,100,302, June 16, 1914.

The object of the invention is to provide improved method and apparatus for producing a cleaner and more accurate separation or classification of the different grades of material and avoiding contamination of one grade by any other grade; which more particularly produces a cleaner coarse grade or grades of the material; and which also automatically maintains a uniform or constant density of the mixture in the grading vessel, so that the grading or classifying operation is carried out under practically unvarying conditions without liability of altering or changing the grade at any level in the grading vessel while the grading operation is going on and thereby contaminating a supply of one grade already separated with material of another grade. The method and apparatus therefore enable finely divided material of this kind to be accurately separated or classified into several definite or distinct grades, each including material the characteristics of whose particles are between definite upper and lower limits and no material having other characteristics.

In the drawings, Figure 1 represents a diagrammatic sectional elevation of one form of grading apparatus embodying the invention; Fig. 2 is a similar view illustrating the application of the invention to a grinding apparatus; Fig. 3 is a view corresponding to Fig. 2 and illustrating a different form of the invention; and Fig. 4 is a detail sectional elevation of the lower portion of the grading vessel.

The method utilizes the general principles

set forth in my prior Patent 1,100,302, and grades or classifies the material while in suspension in a liquid in a grading vessel by the action of a current of liquid having an upward flow or travel relative to a downward movement of the material, which separates and classifies the several grades in different strata or zones in said vessel, the finer grades near the top and the coarser grades near the bottom. The material to be graded has heretofore been introduced into the grading vessel either at its bottom, as in my Patent 1,100,302, or at the upper level of the liquid therein. When introduced at the bottom the finer grades are carried upwardly by the upward flow or travel of the liquid relative to the material, and pass in turn the outlets through which the several coarser grades are withdrawn. This gives practically clean grades in ordinary grading apparatus but a small percentage of the fine material unavoidably passes out through the various openings when the apparatus is run continuously. On the other hand, when the material is introduced at the upper level of liquid in the grading vessel it is necessary to allow considerable time for the material to settle to the proper level before withdrawing the finer grades, or the finer grades withdrawn are contaminated by some of the coarser material, which has to pass downwardly through the finer grades to reach its proper level near the bottom of the vessel.

By my improved method the material to be graded is introduced into the grading vessel at a level intermediate its bottom and the upper level of liquid therein, thereby enabling the coarser material to travel downwardly against the rising current of liquid and the finer grades to travel upwardly with said current, so that all grades of material find their proper levels without contaminating one grade with material from another. The material to be graded may be introduced into the grading vessel in any suitable manner but preferably is in suspension in a liquid, being conducted to and introduced into the grading vessel in the form of a stream of mixture which may flow or travel either upwardly or downwardly, both forms of the invention being shown herein.

The upward flow or travel of the liquid relative to the material may be produced in any suitable manner, such for example as described in by prior Patents, Nos. 934,441, 110

September 21, 1909, 1,056,415, March 18, 1913, and 1,100,302, June 6, 1914, that is, it may be produced by the displacement of the liquid by the solid particles traveling downwardly, the displaced liquid rising to take the place of the falling particles and thereby creating an upward flow of travel of the liquid, or it may be produced by introducing a supply of liquid into or near the bottom 10 of the grading vessel. This liquid, for example, may be that which carries in suspension the particles of material to be graded, the liquid having an upward flow or travel through the grading vessel to the overflow at 15 the top, while the particles of material to be graded or classified have a downward movement relatively to the upward flow of the liquid and seek the levels of their proper grades in said vessel. The best results, however, are obtained when the upward flow or travel of the liquid is produced or augmented by introducing a separate supply of fresh liquid into the grading vessel at or near its bottom and preferably at a level 20 below the level at which the material to be graded is introduced thereinto. This fresh liquid supply has an upward flow or travel relative to the downward movement of the coarser particles of material to be classified 25 and accurately separates or classifies the same into definite grades. The outlet or outlets for the coarsest grade or grades may be located at any suitable level, but are preferably located at a level between the inlet for 30 the fresh liquid supply and the inlet for the material to be graded, so that they lie in a zone or stratum not traversed by any of the finer grades. Consequently, an extra clean coarse grade or grades can be withdrawn 35 from this region of the grading vessel. The fresh liquid supply travels upwardly through the grading vessel with the liquid of the mixture containing the abrading material, but the velocity of the upward 40 flow or travel of the liquid relative to the downward flow of the material at and near the inlet for the mixture is not sufficient to carry any of the coarser particles upwardly, but is merely sufficient to lift the finer grades 45 to their proper levels in the grading vessel.

The mixture of liquid and finely divided material to be classified is preferably introduced into the grading vessel in an upwardly traveling stream, but may be introduced in the form of a stream of mixture having a downward flow or travel relative to the upward flow or travel of the mixture in the grading vessel, and which stream of material is so handled as to be independent 55 of the main body of liquid in the grading vessel, say for example, by introducing it through a downwardly extending pipe or conduit dipping into the mixture in the grading vessel and having its lower end immersed therein to a level above the level of

the outlet for the coarsest grade withdrawn therefrom. The density of the mixture in the grading vessel varies from time to time as the total quantity of material therein to be graded increases or diminishes, and the total quantity of material in the grading vessel varies with the supply thereto and the amounts of the various grades withdrawn at the different outlets. While the downwardly moving stream of mixture introduced into the grading vessel is independent of or separated from the body of liquid therein, nevertheless the density of the body of mixture in the grading vessel affects the velocity of the flow of the stream of mixture being supplied to said vessel. This is due to the fact that the column of mixture in the pipe or conduit through which it is introduced into the grading vessel is balanced against a similar column of the body of mixture in the grading vessel. If the weight or pressure produced by the body of the mixture in the grader is less than that of the column of liquid in the pipe or conduit the preponderating weight of the mixture in the pipe or conduit produces a more rapid downward flow thereof, while, on the other hand, if the weight or pressure produced by the mixture in the grading vessel is greater than that in the pipe or conduit through which the mixture is introduced thereinto, then the preponderating effect of the body of liquid in the grading vessel tends to produce an upward flow of the mixture in the pipe or conduit. This effect partially or completely counteracts the normal downward flow of the mixture in the delivery pipe or conduit to replace the mixture being withdrawn from the grading vessel and causes more or less of the mixture being supplied to the grader to pass out through the overflow and back to the sump, thus shunting the superfluous material around the grader. Consequently the velocity of the downward flow or travel of the mixture through the delivery pipe or conduit varies inversely with the density of the body of the mixture in the grading vessel, increasing as the density decreases and decreasing as the density increases, and has a tendency to automatically govern or regulate the mixture being graded so that it is maintained at a practically uniform or fixed density. Referring to the drawings, Fig. 1 represents the invention applied to apparatus for grading or classifying finely divided material. In many respects the apparatus shown is similar to that of my prior Patent 1,100,302 before referred to. As illustrated, it comprises a primary grading vessel or tank 10 provided with a bottom inlet pipe 11 through which a fresh liquid supply may be introduced for producing the upward flow or travel of the liquid for the grading operation, and also with an overflow outlet 12

through which the excess liquid and mud and the material too fine for further use flow to the sewer. In said primary grader the particles of material are distributed in various strata or zones according to the characteristics of the different particles, and the several classes or grades of material are withdrawn from said grader through separate outlet pipes or conduits 13, 14, 15, 16, 17 and 18. The material passing through any or all of said outlet pipes may be conducted directly to storage or settling tanks to be collected for use or to be ground up into smaller sizes if necessary, but preferably each grade is conducted in suspension in the liquid to an independent secondary grading vessel or tank 19, there being one of said vessels for each grade withdrawn. Said vessels 19 are each provided with a bottom inlet 20 for a clear liquid supply, and with an overflow 21 to carry off the fine material either to the sewer or to a sump or pit to be later regraded. The secondary cones 19 are of the same construction shown in my prior Patent 1,100,302, embodying a conical lower portion 22, a cylindrical intermediate portion 23 and a conical upper portion 24. The upward velocity at the top of the conical bottom should be slightly above the upward velocity in the primary grading cone at the point from which the material conducted to the secondary grader comes, while the upward velocity in the space in the cylindrical part of the grader should be the same as the upward velocity at the point in the primary cone where the next finer grade is withdrawn. The opening to the outlet pipe or conduit 25 from each secondary grading vessel is at a level at or near the bottom of the cylindrical intermediate portion 23 of said vessel, so that a clean grade of material is withdrawn therefrom, said material being conducted to a storage tank 26, in which it may be held in suspension for use as desired, or may be allowed to settle for later use.

The material to be graded is supplied to the primary grader from a mixing tank or lixiviator 30, in which are located power driven paddles or stirrers 31 for mixing the material and putting it in suspension in the liquid. The liquid is introduced to said tank through a suitable pipe and the solid material to be graded may be shoveled in or delivered from a hopper, as desired. The material in suspension in the liquid flows from the tank 30 through a pipe 32 into a mixing cone or funnel 33, from which it passes to the primary grader through a depending pipe or conduit 34 connected to the bottom of the cone 33 and extending down into the mixture in the primary grading vessel. The outlet from the lower end of the pipe 34 may be at any suitable level intermediate the bottom of the grader 10 and

the upper level of the liquid therein, but is shown as at a level between the openings to the outlet pipes or conduits 13 and 14.

Preferably, suitable means is provided for maintaining a constant head of the mixture being supplied to the primary grader, and in the form shown the supply of material to the cone 33 is regulated by a ball float 35 in said cone, which controls a valve 36 in the pipe 32. This ball float maintains a definite level of liquid in the mixing cone 33 and increases the supply through the valve 36 as the level of liquid falls and decreases it as the level of liquid rises.

The depending delivery pipe 34 automatically maintains substantially a uniform density of the mixture in the primary grading vessel with the several grades to be withdrawn therefrom at substantially constant levels. As the density of the body of the mixture in the primary grading vessel increases there is an increasing tendency to counteract or retard the downward flow or travel of the mixture being delivered to said primary grader through the pipe 34, and if an over supply of material collects in the primary grading vessel further supply of material from the lixiviator 30 is held back until further material is withdrawn from the primary grader through the several outlets therefrom. If the density of the material in the primary grading vessel decreases by insufficient supply or too rapid withdrawal of the several grades therefrom the opposition to the downward flow or travel of the mixture through the pipe 34 decreases and a greater supply of material passes through the lixiviator to the primary grading vessel.

This arrangement produces a series of very clean definite grades of material with practically unvarying characteristics in each of the several grades as soon as the grader has operated long enough to reach a stable condition.

Fig. 2 illustrates the invention applied for grading finely divided material, such as sand or the like, and supplying the same directly to a grinding apparatus. In the apparatus shown 40 represents the grinding table equipped with the usual runners 41 and surrounded by a gutter 42 leading to the ditch 43 through which the used material flows to the sump or pit 44, provided with the usual waste overflow 44^a to the sewer, for eliminating the excess water and slimes from the system. The abrasive is supplied to the grinding table in suspension in a liquid from a grading vessel or cone 45 having a plurality of withdrawal pipes 46, 47, 48, the inlets to which are at different levels in said vessel, said pipes being provided with suitable valve mechanism enabling material to be delivered from any one or more of said pipes to a trough 49 through which it flows to the grinding table. An

overflow pipe 39 conducts the waste material from the grader 45 to the ditch 42. So far as described to this point the apparatus may be of the same kind shown, for example, in 5 Fig. 1 of my prior Patent No. 1,089,705, March 10, 1914.

According to the present invention the material to be graded is delivered in suspension in a liquid to the grading vessel 10 45 through a depending pipe or conduit 50 whose bottom opening is immersed in the liquid in said vessel at a level intermediate the levels of the openings to the outlet pipes 46 and 47. The bottom of the grading 15 vessel is provided with an inlet 51 for a clear liquid supply to produce or augment the upward flow or travel of the liquid relative to the material. The coarse particles in the material to be graded passing in 20 through the pipe 50 fall downwardly against the rising current from the inlet 51, the velocity of said current being sufficient to lift the finer particles of material before they have a chance to fall to the outlet for 25 the coarsest grade. Consequently a very clean, coarse grade of material may be withdrawn from the pipe 46. The finer grades rise to the levels of the outlets for the finer grades, but no coarse material is carried up with the fine, so that the several 30 finer grades are clean and free from contamination by the coarser grades.

The material to be graded is supplied to the pipe 50 from a supply box or vessel 52, 35 located at the upper end of the pipe 50 and provided with a suitable hand-operated valve 53 for allowing or shutting off the flow of material from said vessel to the pipe 50. Material is supplied to said vessel 40 in any suitable manner, such as by a centrifugal pump 54, the inlet to which dips into the sump or pit 44, and which pump supplies material to the vessel 52 through the pipe 55. Vessel 52 is also supplied with 45 an overflow pipe 56 delivering to the sump and connected to said vessel 52 at a level above the valve 53, so that when said valve is open a constant head or level of liquid is maintained in the vessel 52 at the level 50 of the overflow pipe 56.

In operation of this system the valve 53 is open and the material delivered by the pump passes downwardly to the grading vessel 45 through the pipe 50, the excess 55 flowing back to the sump through the overflow 56. The absolute density of the body of the mixture always depends upon the exact head of the overflow 56 above the level of liquid in the grading vessel, which 60 head is constant and produces the downward flow of the supply of material to the grader. The vertical depending pipe 50 with its opening below the level of the liquid in the tank 45 automatically regulates the flow of 65 material to the grading vessel in accordance

with variations in the density of the mixture in said vessel, as before described; and it also produces very clean grades of material at the different levels in the grading vessel so that the grinding operation is more effective and may be carried on with greater rapidity. Throughout the grading operation material may be discharged to the grinding table with the several grades in any desired order or sequence and constantly 70 in suspension in a liquid, and furthermore, the material flowing off from the grinding table passes back to the sump and again up to the grading vessel, so that a complete cycle of circulation is going on during the 75 entire grinding operation. Fresh coarse material is added from time to time to the sump, usually a new measured batch before each grinding operation.

Figs. 3 and 4 illustrate another arrangement for securing very clean grades of material at the different levels in the grading tank, but which omits the automatic regulation of the supply of material to the grading vessel in accordance with the density of 80 the material therein. In this form the circulation of the material to and from the grinding table is the same as in the form before described, the material passing out from the grading vessel through the several 85 outlets 46, 47, 48 to the grinding table, thence to the sump and thence back into the grading vessel. The material is delivered from the sump to the grading vessel 45^a by a centrifugal pump 54^a, which discharges 90 into the grading vessel through a nozzle 60 at the bottom of said vessel and which extends part way up into the same, its outlet 61 being at a level above the level of the opening to the withdrawal pipe 46 for 95 the coarsest grade of material. The grading vessel is also provided at or near its extreme bottom, and at a level below the level of the outlet for the coarsest grade, with an inlet 62 for a supply of clear liquid. The finer 100 particles delivered to the grading vessel by the nozzle 60 pass directly upwardly to their various levels in the grading vessel, and as no coarse material passes through the levels of the finer grades the latter are withdrawn 105 in a clean condition uncontaminated by the coarser material. The coarse material falls downwardly from the outlet 61 against the rising stream of clear liquid from the inlet 62. This rising stream prevents any of the 110 finer grades from flowing through the outlets for the coarse grade or grades, so that a very clean, coarse grade of material is withdrawn from this region in the grading vessel. The auxiliary water supply also enables the operator to control the density of 115 the grinding mixture without changing the velocity of flow from the pump or appreciably varying the grading velocity for the 120 finer grades.

In both of the systems shown respectively in Figs. 2 and 3 the finishing operation is carried on with the finer grades collected in the upper strata of the grading vessel during the grinding or facing operation, by withdrawing the finer grades successively and in any desired sequence to the grinding table. During this operation the supply of material to the grader may be shut off but 10 preferably goes on continuously during the entire operation of grinding and finishing.

What I claim is:

1. The method of grading finely divided material mixed with a liquid, consisting in 15 subjecting said material in a vessel to an upward flow or travel of the liquid relative to the material and thereby separating the material into grades, withdrawing different grades from said vessel independently and 20 from different levels therein, introducing the material to be graded into said vessel at a level above the level of the coarsest grade and below the level of the next finest grade withdrawn therefrom, and simultaneously introducing liquid into said vessel below the level from which the coarse material is withdrawn.

2. The method of grading finely divided material mixed with a liquid, consisting in 30 subjecting said material in a vessel to an upward flow or travel of the liquid relative to the material and thereby separating the material into grades, introducing said material in suspension in a liquid into said vessel at a level intermediate the levels of the coarsest and useful finest grades withdrawn therefrom, simultaneously withdrawing coarse useful material from a level below and fine material from a level above the 35 level at which the material is introduced to said vessel, and simultaneously introducing liquid into said vessel at a level below the level at which the material is introduced thereto.

45 3. The method of grading finely divided material mixed with a liquid, consisting in subjecting said material in a vessel to an upward flow or travel of the liquid relative to the material and thereby separating the material into grades, introducing said material under a constant head in suspension in a liquid into said vessel at a level intermediate the levels of the coarsest and finest grades withdrawn therefrom by a downwardly 50 moving stream of mixture independent of the upward flow or travel of the liquid in said vessel, to thereby control the flow of said stream by the density of the mixture in said vessel, and withdrawing several grades 55 from said vessel separately and independently.

4. The method of grading finely divided material mixed with a liquid, consisting in subjecting said material in a vessel to an 60 upward flow or travel of the liquid relative

to the material and thereby separating the material into grades, introducing said material under a constant head in suspension in a liquid into said vessel at a level intermediate the levels of the coarsest and finest 70 grades withdrawn therefrom by a downwardly moving stream of mixture independent of the upward flow or travel of the liquid in said vessel, to thereby control the flow of said stream by the density of the mixture in 75 said vessel, and withdrawing coarse material from a level below and fine material from a level above the level at which the material is introduced into said vessel.

5. The method of grading finely divided material mixed with a liquid, consisting in 80 subjecting said material in a vessel to an upward flow or travel of the liquid relative to the material, and thereby separating the material into grades, introducing the material to be graded into said vessel at a level intermediate the levels of the coarsest and finest grades withdrawn therefrom, simultaneously withdrawing a coarse grade from said vessel at a level below the level at which 90 the material is introduced thereto, withdrawing a useful fine grade from said vessel at a level above the level at which the material is introduced thereto, and simultaneously introducing liquid into said vessel at 95 a level below the level at which the material is introduced thereto.

6. Apparatus for grading finely divided material mixed with a liquid, comprising a grading vessel, means for producing therein 100 an upward flow or travel of the liquid relative to the material to separate the material into grades, means for independently withdrawing different grades from different levels in said vessel, means for introducing 105 the material to be graded into said vessel at a level intermediate the level of the coarsest and next finest grades withdrawn therefrom, and means for simultaneously introducing liquid into said vessel below the level from 110 which the coarse material is withdrawn.

7. Apparatus for grading finely divided material mixed with a liquid, comprising a grading vessel, means for producing therein an upward flow or travel of the 115 liquid relative to the material, means for withdrawing several different grades from different levels in said vessel, a conduit for supplying material to be graded extending into said vessel and terminating at a level 120 intermediate the levels of the coarsest and finest grades withdrawn therefrom, and means for introducing a liquid supply to said vessel at a level below the level of the coarsest material withdrawn therefrom. 125

8. Apparatus for grading finely divided material mixed with a liquid, comprising a grading vessel, a conduit for supplying material to be graded in suspension in a liquid to said vessel, said conduit opening into 130

6
said vessel at a level intermediate its bottom and the upper level of the liquid therein, said vessel being provided with an overflow, means for returning the material from 5 said overflow to the vessel for regrading, an outlet for withdrawing the coarse material from the vessel at a level below that at which the material is introduced thereinto, and outlets for withdrawal of the finer material 10 at levels above that at which the material is introduced thereinto.

9. Apparatus for grading finely divided material mixed with a liquid, comprising a grading vessel, a conduit, for supplying material to be graded in suspension in a liquid to said vessel, said conduit opening into said vessel at a level intermediate its bottom and the upper level of the liquid therein, said vessel being provided with an 15 overflow, means for returning the material from said overflow to the vessel for regrading, outlets for withdrawing the coarse material from a level below, and outlets for withdrawing the fine material from levels 20 above that at which the material is introduced into the vessel, and a liquid supply pipe connected to said vessel at a level below that at which the coarsest material is withdrawn. 25

10. Apparatus for grading finely divided material mixed with a liquid, comprising a grading vessel, means for producing therein an upward flow or travel of the 30

liquid relative to the material, outlets for withdrawing the various grades from different levels in said vessel, an overhead supply reservoir for material to be graded mixed with water, a conduit extending downwardly therefrom into said reservoir and terminating at a level intermediate the levels 35 of the coarsest and finest grades withdrawn therefrom, and a liquid supply to said vessel at a level below the level of the coarsest material withdrawn therefrom.

11. Apparatus for grading finely divided material mixed with a liquid, comprising a grading vessel, means for producing therein an upward flow or travel of the liquid relative to the material, outlets for withdrawing the various grades from different levels in 40 said vessel, an overhead supply reservoir for material to be graded mixed with water, a conduit extending downwardly therefrom into said reservoir and terminating at a level intermediate the levels of the coarsest and 45 finest grades withdrawn therefrom, means to maintain a constant head of liquid in said supply reservoir, and a liquid supply to said vessel at a level below the level of the coarsest material withdrawn therefrom. 50

60 In testimony whereof I have hereunto set my hand.
